(57) **CLAIM**

The ornamental design for a high performance balance, as shown and described.

DESCRIPTION

FIG. 1 is a top right perspective view of the high performance balance;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top right perspective view of a second embodiment of the high performance balance;

FIG. 9 is a top right perspective view of a third embodiment of the high performance balance showing the top plate;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is a top right perspective view of a fourth embodiment of the high performance balance.

The broken lines depict portions of the high performance balance that form no part of the claimed design.
